(57) **CLAIM**

The ornamental design for a housing for water monitoring device as shown and described.

DESCRIPTION

FIG. 1 is a front side perspective view of a housing for a water monitoring device showing the claimed design; FIG. 2 is another front side perspective view thereof; FIG. 3 is a bottom front perspective view thereof; FIG. 4 is a rear side perspective view thereof; FIG. 5 is a front view thereof;

FIG. 6 is a rear view thereof;

FIG. 7 is a side view thereof;

FIG. 8 is another side view thereof;

FIG. 9 is a top view thereof; and,

FIG. 10 is a bottom view thereof.

The housing for water monitoring device is shown with symbolic breaks in the upper and lower section of disclaimed cylindrical feature in FIGS. 1–8 drawing views. It is understood that patentability is based only on those portions of the article that are shown in solid lines, and the appearance of any portion of the article between the break lines forms no part of the claimed design.

The broken lines shown are included for the purpose of illustrating portions of the housing for water monitoring device that form no part of the claimed design.
